UNITED STATES PATENT OFFICE.

BURDETT LOOMIS, OF HARTFORD, CONNECTICUT, AND HAWLEY PETTIBONE, OF NEW ROCHELLE, NEW YORK, ASSIGNEES TO LOOMIS-PETTIBONE GAS MACHINERY COMPANY, A CORPORATION OF NEW JERSEY.

APPARATUS FOR MANUFACTURING AND MIXING GASES.

No. 833,137.

Specification of Letters Patent.

Patented Oct. 9, 1906.

Application filed December 7, 1903. Renewed March 14, 1906. Serial No. 306,014.

To all whom it may concern:

Be it known that we, BURDETT LOOMIS, residing at Hartford, in the county of Hartford and State of Connecticut, and HAWLEY PETTIBONE, residing at New Rochelle, in the county of Westchester and State of New York, citizens of the United States, have invented new and useful Improvements in Apparatus for Manufacturing and Mixing Gases, of which the following is a specification.

This invention relates to apparatus for making and delivering gas of any desired calorific value or the desired proportion of heat units adapted for heating purposes and for motive power in high-power gas-engines.

The object of our invention is to provide for generating producer-gas and water-gas, drawing them off from the generator by an exhauster, and during the manufacture and the operation of the exhauster mixing the two kinds of gas in any desired proportion for giving the most effective and economical results as a motive power in explosion-engines of several hundred horse-power or as a fuel in metallurgical operations.

In the usual method of making producer-gas air and steam are together forced up through a body of incandescent fuel, generating a mixed gas of variable quality. It is difficult with the varying output of gas from a gas-producer to maintain the proper and uniform proportions of air and steam admitted to the fuel or decomposed therein. It is also difficult to decompose all of the steam into hydrogen and carbon monoxide. When the proportions of air and steam change, the quality of the gas varies both in its component parts and in calorific value or power.

By passing air and steam alternately through a body of incandescent fuel in a cupola-generator each kind of gas—producer and water gas—is made of uniform quality, and by mixing these gases in fixed proportions the product is a more constant and uniform quality of gas well adapted for operating high-power gas-engines. We have therefore devised apparatus particularly adapted for making and delivering such a mixed gas to a holder or directly to the place of use.

The matter constituting our invention will be defined in the claims.

Our gas generating and mixing apparatus is illustrated in the accompanying drawings, in which—

Figure 1 represents a side elevation of the apparatus. Fig. 2 represents a rear elevation of the connected generators and steam-boiler with one generator in section. Fig. 3 represents a top plan view of the apparatus.

The generators A and B are constructed of brick inclosed in iron jackets in the usual manner and are provided with grates b, preferably composed of brick arches, and with ash-pits X. The generators are connected at the top by a pipe or flue C and are connected at the base or ash-pits X by gas-outlet pipes D D', having valves d d', with the base of the tubular steam-boiler E having at top and bottom the gas-chambers e e'. A gas-outlet pipe F, having a valve f, connects with the upper gas-chamber e and with the base of the scrubber G, and a gas-outlet pipe H, having a valve h, leads from the top of the scrubber down to the main gas-exhauster K.

The main gas-take-off pipe L leads from the under side of the exhauster and connects by the branch pipe L', having a valve l', with the holder O for producer-gas or for a mixture of producer-gas and water-gas.

The exhauster K is driven by the engine I, having a shaft i, which is coupled directly to the shaft of the exhauster. The opposite end of the shaft i is provided with a cone-pulley g, which connects by a belt o with a cone-pulley g' on the shaft of the auxiliary exhauster R.

A branch pipe having a valve l connects pipe L with the purge-stack M for the escape of waste gases or products of combustion. A branch pipe N, having a valve n, leads from the pipe L into holder P for water-gas. The pipe T, having a valve t, leads from the holder P and connects with the top of the small exhauster R. The discharge-pipe T' from exhauster R is provided with a valve t' and connects with pipe L' beyond its valve l' for supplying a definite proportion of water-gas and mixing it with the producer-gas which is being passed through pipe L' into the holder O.

A circulating-pipe r, having a valve r', connects the outlet-pipe T' with the inlet-pipe T of the exhauster R. A circulating and by-pass pipe k connects the outlet-pipe L with the inlet-pipe H of the exhauster.

K and is provided with the valve k' . Steam-supply pipes S and S' connect by branch pipes s and s' , each having a valve, with the top and bottom of each of the generators A 5 and B for supplying steam to be passed either up or down through the bodies of incandescent fuel in making water-gas. A gas-outlet pipe Q, having a valve q , leads from holder O for taking mixed producer-gas and 10 water-gas to a gas-engine or other place of use.

The operation of making and mixing producer-gas and water-gas may be conducted as follows: Fires are kindled on the grates in 15 generators A and B and at first allowed to burn by natural draft while fuel is gradually fed in and ignited. The valves l' and n being closed and the stack-valve l and other valves between the stack and generators being open and the lids z wholly or partly open, the exhauster K is operated to draw air down 20 into the bodies of ignited fuel and the resulting gas off from the bases of the generators through boiler E and scrubber G and dis- 25 charge it up the stack M. As soon as good producer-gas is generated the stack-valve l is closed and valve l' opened, and the producer-gas is discharged into the holder O. The stack-valve l is only open while the 30 bodies of fuel are being heated to the proper condition for making gas. Deep bodies of fuel in generators A and B having been heated to incandescence, water-gas may be made, and for this purpose the top lids z are closed, 35 valve d' closed, valve l' closed, valve n opened, and steam-valve s' opened, admitting steam into the ash-pit of generator A. Steam passes up into the body of incandescent fuel in generator A, where it is decom- 40 posed, and the resulting water-gas passes through top pipe C into generator B and thence down through the body of incandescent fuel therein, where any accompanying vapors are decomposed and carbonic acid 45 converted into carbon monoxid, making a well-fixed high-grade water-gas. This gas is drawn off by the exhauster through pipe D, boiler E, and scrubber G and discharged into the water-gas holder P. Water-gas is thus 50 made until the temperature of the fuel is reduced too low for effectively decomposing steam, and then the steam is shut off, the top lids z opened, valve d' opened, valve n closed, and valve l' opened and producer-gas again 55 made and delivered into the holder O. When it is again desired to make water-gas, we preferably close valve d in gas-outlet pipe D and admit steam into the base of generator B. Steam is then decomposed by a passage up 60 through the incandescent fuel in generator B and the resulting gas down through the bed of fuel in generator A, and the resulting wa- 65 ter-gas is drawn off by the exhauster through pipe D', the steam-boiler, and scrubber and discharged into holder P. When it is thought

desirable, steam may be admitted through the valves s into the top of the generators A and B and passed down through the beds of fuel, together with air admitted by opening lids z , thus making an enriched producer-gas—that is, a mixture of water-gas and producer-gas. It has been found of great advantage to make occasional runs of water-gas in downdraft gas-generators by passing steam alternately up through one body of 70 fuel and the resulting gas down through the other body of fuel, as above described. These runs keep the fires in better condition, and the mixed gas resulting from mixing producer-gas and water-gas in definite proportions is more uniform in quality than it is possible to make by the continuous producer-gas system. A fixed clean uniform 75 quality of gas of fairly high flame temperature can be delivered at any desired pressure from the above-described apparatus, and it can be made from bituminous coal, anthracite coal, coke, or wood without any change being made in the apparatus. A sufficient quantity 80 of water-gas having been stored in the holder P, the auxiliary exhauster R is used to deliver a fixed proportion of water-gas with producer-gas into the holder O for mixed gas. The exhauster R and the valves r' and t' are operated as follows: When the exhauster 85 K is operating and delivering producer-gas through valve l' , the valves t and t' are open and the by-pass valve r' closed, and the exhauster R will operate to draw water-gas from the holder P and deliver it through pipe 90 T' into the holder O at a rate proportional to the delivery of producer-gas by the exhauster K. By shifting the belt o on the cone-pulleys g and g' the proportion of water-gas to producer-gas can be increased or decreased. 95 The mixture of water-gas and producer-gas in definite and any desired proportions can thus be stored in the holder O and delivered to gas-engines or other places of use. When water-gas is being delivered through valve n to the holder P, valve t' is closed and the by-pass valve r' is opened, so that no water-gas passes into the mixed-gas holder O except when producer-gas is also being delivered 100 into said holder O. In case it should be desired to close valve h in the gas-pipe H while the exhauster K is running the valve k' in the by-pass pipe k may be opened, so that gas will simply be circulated through the pipes H, L, and k . 105

The process or method of making, delivering, storing, and mixing gases of any desired calorific value and in any desired proportions of their constituents relative to their heat units to adapt them for use as motive power 110 in high-power gas-engines and for other purposes is not claimed herein, as it is made the subject of a separate application for patent, Serial No. 334,792, filed September 15, 1906.

Having described our invention, what we 115

claim, and desire to secure by Letters Patent, is—

1. The combination with a cupola gas-generator, of a connecting-exhauster for drawing off producer-gas from the generator, a storage gas-holder and a pipe connecting the exhauster with the holder, a separate water-gas holder and means, connecting with both holders, for supplying a definite proportion of gas from one holder to the other, whereby producer-gas and water-gas may be mixed in the desired proportion for supplying gas-engines.

2. The combination with a cupola gas-generator, adapted for making producer-gas and water-gas, of a connecting-exhauster for drawing off both kinds of gas, two storage gas-holders, a pipe leading from the exhauster and connecting by branch pipes, each having a valve, with said holders and means connecting with the holders for passing a desired proportion of gas from one holder to the other for making a suitable mixture of producer-gas and water-gas for operating gas-engines.

25 3. The combination with a cupola gas-generator, adapted for making producer-gas and water-gas, of a connecting-exhauster, two gas-holders, pipes having valves connecting the outlet of the exhauster with said holders, an auxiliary gas-exhauster connecting by valved pipes with both holders, and operating-gearing connecting both of said exhausters, substantially as described.

4. The combination with a cupola gas-generator having means for supplying air and steam, of a connecting-exhauster K, two gas-holders O and P, valved pipes L' and N connecting with said exhauster and holders, the

auxiliary exhauster R connecting by valved pipes with both of the holders and operating- 40 gearing connecting both of said exhausters, substantially as described.

5. The combination with a cupola gas-generator adapted for making producer-gas and water-gas, of a connecting-exhauster K, having a cone-pulley on its shaft, two gas-holders, valved pipes connecting said exhauster with the holders, the auxiliary exhauster R, having a cone-pulley on its shaft, a belt on the cone-pulleys of both exhausters, and 50 valved pipes connecting exhauster R with both of the holders, substantially as described.

6. Gas generating and mixing apparatus comprising two cupola-generators connecting 55 at the top and having air-inlets at the top, a steam-supply pipe and a valved gas-outlet pipe connecting with the base of each generator, an exhauster connecting with said outlet-pipes for drawing off producer-gas and 60 water-gas, two storage-holders, valved pipes connecting the exhauster with both of the holders, a separate valved pipe connecting the holders and means connecting with said pipe for drawing gas from one holder and 65 supplying it to the other holder for making a mixture of producer-gas and water-gas for operating gas-engines and other purposes.

In testimony whereof we have signed our names to this specification in the presence of 70 two subscribing witnesses.
